JAMES OLIVER KAFADER, OF FORT BIDWELL, CALIFORNIA, ASSIGNOR OF ONE-HALF
TO E. T. VAUGHAN, OF FORT BIDWELL, CALIFORNIA.

WELL-CASING DRILL.

1,127,011.

Specification of Letters Patent.

Patented Feb. 2, 1915.

Application filed February 4, 1914. Serial No. 816,650.

To all whom it may concern:

Be it known that I, JAMES O. KAFADER, a citizen of the United States, and a resident of Fort Bidwell, in the county of Modoc and State of California, have invented 5 a new and Improved Well-Casing Drill, of which the following is a full, clear, and exact description.

This invention relates to a well casing 10 drill for the purpose of drilling holes in a well casing in those regions where there are strata of water in the earth.

The general objects of the invention are to improve and simplify the construction 15 and operation of well casing perforators of the drill type so as to be reliable and efficient in use, comparatively inexpensive to manufacture and keep in operative condition, and so designed as to be easily and 20 quickly manipulated and positioned.

Another object of the invention is the provision of a tool of the character referred 25 to which includes a tool suspension and drill driving shaft which is rotated by suitable means at the top of the well casing.

A further object of the invention is the provision of means operable from a point 30 at the top of the well casing for effecting the feed of the drill, and coacting therewith is an extracting device which automatically extracts, when the feeding means is returned 35 to normal position, the drill from the hole after the latter is drilled.

A further object of the invention is the provision of a drill in which the body is 40 mounted on the drill driving and tool suspension rod, and the feeding means embodies a sliding wedge movable longitudinally of the body and arranged to engage a thrust member or abutment pivotally mounted upon the body, and on the shaft 45 is provided means with which the said wedge, when in initial position, is adapted to interlock, so that the body and shaft can be turned as a unit to bring the drill to the next point where a hole is required.

With such objects in view, and others which will appear as the description proceeds, the invention comprises various novel 50 features of construction and arrangement of parts which will be set forth with particularity in the following description and claims appended hereto.

In the accompanying drawings, which

illustrate one embodiment of the invention, 55 and wherein similar characters of reference indicate corresponding parts in all the views, Figure 1 is a vertical section of a sunken well casing, showing the tool in position therein for the purpose of drilling 60 holes, and showing the body of the tool in elevation; Fig. 2 is an enlarged sectional view of the tool taken longitudinally and showing the position of the parts prior to the drill being set for boring; Fig. 3 is a 65 similar view showing the drill in operation; Fig. 4 is a side view of the tool; Figs. 5 and 6 are horizontal sections on the lines 5—5, 6—6, respectively, Fig. 2; and Fig. 7 is an enlarged sectional view of the drill 70 and chuck therefor.

Referring to the drawings, A designates a well casing which is provided with a cap or equivalent means a at its upper end which serves to form a support for the drilling 75 tool designated generally by B, which tool is adapted to be lowered into the casing to the required depths for the purpose of drilling holes in the casing at the various strata of water through which the well casing has 80 been driven, whereby the water can enter the casing through the holes. In the present instance the casing is shown as passing through two strata c of water, and the casing A is shown as having openings a' drilled therein at such strata. 85 The tool is adapted to drill one hole at a time and is hence capable of being adjusted from point to point where the holes are required. 90

The tool B comprises an elongated body 1 which is made of a strip of metal bent U-shaped into side members 2 and a connecting portion 3. Between the lower or free ends of the side members 2 95 are blocks 4 and 5 which are spaced apart from each other and are secured to the members 2 by pins or rivets 6. By this arrangement a chambered frame or body is formed which is opened at two sides. The body or 100 frame 1 is suspended on the lower end of a shaft 7 that is made in sections and united by a coupling 7' so that the shaft can be lengthened or shortened to reach any desired depth in the well casing. The shaft is 105 rotatable in bearings 8 at the top of the frame body 1 and 9 in the bearing block 4, and on the lower end of this shaft is a

bevel gear 10 which meshes with a bevel gear 11 on the chuck 12 which has its spindle or shaft 13 journaled in a horizontal bearing 14 formed in the lower block 5. 5 In this chuck 12 is fastened in any suitable manner the twist or other drill 15 which has its axis at right-angles to the axis of the shaft 7.

On the upper end of the shaft 7 is a suspending collar or equivalent device 16 which suspends the entire tool on the cap 10 in such a manner as to permit the shaft to be rotated, such rotation being produced by a crank or equivalent device 17.

15 The tool embodies a feeding means which is mounted on the body or frame 1 of the tool and is controllable from the top of the well casing. This drill feeding means comprises a wedge 18 which is slidably mounted within the body 1 and operates on a thrust element or abutment 19 which is mounted in the body 1 at the side opposite from the wedge 18 and is adapted to be thrown laterally by the wedge so as to engage the pipe. 20

25 The wedge 18 has a stem 20 which slides in a bearing 21 in the upper part 3 of the frame 1, and this stem terminates in an eye 22 to which is connected the lower end of a pull cord or element 23 that extends upwardly to and out of the cap *a* on the well casing. A helical compression spring 24 is arranged on the stem 20 of the wedge and interposed between a shoulder 25 on the wedge and the bearing 21 for the stem, 30

35 whereby the spring urges the wedge downwardly to its initial or inoperative position. The lower or thickest end of the wedge is provided with a longitudinal groove 26 so that the wedge can straddle or embrace the

40 shaft and thus take up less room. The inclined surface 27 of the wedge is adapted to engage the inclined surface 28 of the thrust element 19, so that when the wedge is raised, the thrust element is thrown out of the body 45

of the tool and engaged with the well casing. To guide the lower end of the wedge and to resist the lateral thrust due to its wedging action, lugs 29 extend from the sides of the wedge and are movable in 50 slots 30 in the side members 2 of the body of the tool. In order to adapt the tool for operation on well casings of different diameters, the thrust element or abutment 19 has a removable section 19^a which can be taken

55 off and a section of different proportion substituted. The lower end of this section 19^a has a lug 31 which enters an opening 32 in the body section 19^b of the thrust element, while a screw 32^a serves to fasten the upper

60 end of the section 19^a to the section 19^b. The upper end of the section 19^b of the thrust element is connected by a pivot 33 with the upper part of the tool body.

65 It is desirable to automatically extract the drill from a hole that is drilled in the well

casing, and for this purpose an extractor 34 is fastened to the lower end of the body of the tool. This extractor is in the form of a doubled leaf spring which has the end 35 secured to the tool body by a screw 36 at the side opposite from the drill 15, and the other or free end 37 of the extractor extends transversely of the drill 15 and has an opening 38 into which the drill 15 is adapted to enter. Normally the spring 15 stands outwardly beyond or flush with the tip of the drill, but when the tool is in operation the spring or extractor yields as the drill is fed forwardly, this feed being effected by the wedge 18 operating on the thrust element or abutment 19. When, however, the drilling is finished and the wedge 26 is returned to initial position the extractor 34, which has in the meantime been compressed, will expand and extract the drill from the hole. 85

In operation, the tool is lowered into the well casing to the proper depth and suspended, as shown in Fig. 1. The operator then pulls upwardly on the cable 23, which has the effect of setting the tool ready for operation by reason of the wedge 18 being lifted and forcing the abutment element 19 against the well casing at one side and the drill against the well casing at the opposite side. While an upward pull is maintained on the cable 23 the operator turns the crank 17, and by reason of this the drill 15 is rotated and the constant pull on the cable will cause the drill to feed as the hole is being bored. The extractor during this drilling 100 operation is engaged with the well casing, and consequently becomes compressed as the drill proceeds through the wall of the casing, and when the operator feels that the hole is completely drilled by the diminution 105 in resistance, he releases the cable 23, whereby the wedge is shifted downwardly by the expansion of the spring 24. The abutment element 19 gravitates to a pendant position, and the spring extractor expands so as to withdraw the drill from the hole in the well casing. The tool is now turned to a new position for enabling another hole to be drilled. A clutch or locking means must be provided to cause the body of the tool and shaft 7 to 110 turn as a unit in bringing the drill to a new position. For this purpose a pin or equivalent device 36 is provided on the lower end of the shaft 7 so as to enter the groove or socket 26 provided in the lower edge of the wedge 18, so that when the wedge is in lowered position it prevents the shaft from turning independently of the body of the tool. After the tool is turned to a new position the operator again pulls upwardly on the cable 115 23, and in so doing sets the tool for drilling. The crank 17 is again turned so as to rotate the drill 15, and simultaneously the drill is fed by the constant upwardly-maintained pull upon the cable. It will thus be seen 120 125 130

that the tool can be readily adjusted or positioned to drill a number of holes in the well casing with great despatch and ease.

From the foregoing description taken in connection with the accompanying drawings, the advantages of the construction and method of operation will be readily understood by those skilled in the art to which the invention appertains, and while I have described the principle of operation, together with the device which I now consider to be the best embodiment thereof, I desire to have it understood that the device shown is merely illustrative, and that such changes may be made when desired as are within the scope of the appended claims.

Having thus described my invention, I claim as new and desire to secure by Letters Patent:

20 1. A well casing drilling tool comprising a body, a shaft rotatably mounted therein, a drill on the body and connected with the shaft, a well-engaging thrust member comprising a part movably mounted on the body and another part adapted to engage the well casing to be drilled and being removable so as to be adapted to be interchanged with other parts to adapt the tool for well casings of different diameters, and 25 30 a movably mounted element on the said body arranged to engage the first-mentioned part of the said thrust member to cause the said member to engage the well casing and feed the tool bodily to advance 35 the drill as the drilling operation proceeds.

2. A well casing drilling tool of the class described comprising a body, a shaft journaled in the lower end thereof and adapted to extend to the top of the well casing, a 40 drill operated by the shaft, means mounted on the body and movable into engagement with the well casing at the side opposite from that in which the hole is to be drilled, and a longitudinally movable element 45 mounted on the shaft and operable from the top of the well casing for operating said means.

3. A well casing drilling tool comprising a body, a shaft rotatably mounted therein, 50 and forming suspension means for the body, a drill disposed at right-angles to the shaft and operatively connected therewith and extending from one side of the body, a well-engaging thrust element extending from the 55 opposite side of the body, and a device mounted on and movable longitudinally of the body for engaging the said element for producing a feeding movement of the drill.

4. A well casing drilling tool comprising 60 a body, a shaft rotatably mounted therein and forming suspension means for the body, a drill disposed at right-angles to the shaft and operatively connected therewith and extending from one side of the body, a well- 65 engaging thrust element extending from the

opposite side of the body, a device mounted on and movable longitudinally of the body for producing a feeding movement of the drill, and a spring for returning the device to normal position.

5. A well casing drilling tool comprising a body, a shaft rotatably mounted therein and forming suspension means for the body, a drill disposed at right-angles to the shaft and operatively connected therewith and extending from one side of the body, a well-engaging thrust element extending from the opposite side of the body, a device mounted on and movable longitudinally of the body for producing a feeding movement of the 70 75 80 drill, and an extractor mounted on the body and arranged to remove the drill from the hole drilled thereby.

6. A drill of the class described comprising a body, a drill carried thereby, means 85 for rotating the drill, a member carried by the body and serving to move the latter laterally to effect the feeding movement of the drill, and a wedge movably mounted on the body and arranged to engage the said 90 member to force the latter laterally from the body.

7. A drill of the class described comprising a body, a drill carried thereby, means 95 for rotating the drill, a member carried by the body and serving to move the latter laterally to effect the feeding movement of the drill, a wedge movably mounted on the body and arranged to engage the said member to force the latter laterally from the 100 body, and a spring mounted on the body and having one end disposed adjacent the drill for extracting the latter from the hole drilled thereby when the wedge returns to normal position.

8. A tool of the class described comprising a body having a longitudinal chamber open at opposite sides, a pivoted thrust element in one open side of the chamber, a wedge disposed in the other open side and arranged to engage the said element for moving the latter outwardly, a drill carried by the body, means for rotating the drill, means for returning the wedge to normal position for permitting the thrust element to return to inward position, and means for automatically extracting the drill by moving the body of the tool laterally when the thrust element returns to normal position.

9. A tool comprising a body, a shaft extending longitudinally thereof, a wedge movable along the shaft, means for moving the wedge in one direction, a spring for returning the wedge, a thrust element engaged by the wedge and moved laterally from the body and arranged to automatically return to normal position when the wedge is moved by the spring to normal position, and means on the body for extracting the drill from the work.

10. A tool of the class described comprising a body, a shaft rotatable therein, a drill holder operatively connected with the shaft, a feeding means mounted on the body, and means between the feeding means and shaft for causing the body and shaft to turn as a unit.

11. A tool comprising a body, a shaft rotatable therein, a thrust element pivoted on the body, a wedge on the body and arranged to move the thrust element outwardly, means on the shaft with which the

wedge engages when in normal position for permitting the shaft and body to turn as a unit, and a drill holder mounted on the body and operatively connected with the shaft.

In testimony whereof I have signed my name to this specification in the presence of two subscribing witnesses.
